UNITED STATES PATENT OFFICE

2,496,992

ANTISIPHONING DEVICE

Arthur R. Glidden, Seattle, Wash.

Application October 15, 1946, Serial No. 703,312

2 Claims. (Cl. 220—86)

1

This invention relates to a perfected protective device for the gasoline tanks of automotive vehicles, and has for its objects to provide a guard structure arranged and adapted to occupy a position within the filling pipe of the tank, one which may be installed with ease and expedition, which may thereafter be withdrawn only with considerable difficulty, and which most efficiently performs its intended end and namely that of permitting relatively free introduction of gasoline through the pipe into the tank while effectively blocking the admission of a siphon tube.

With the foregoing and other more particular objects and advantages in view, and which will appear and be understood in the course of the following description and claims, the invention consists in the novel construction and in the adaptation and combination of parts hereinafter described and claimed.

In the drawings:

Figure 1 is a side elevational view of my improved guard device shown applied to the filler pipe of a gasoline tank, the filling cap for the pipe being deleted and only the upper end of the pipe being represented in the view.

Fig. 2 is a horizontal sectional view on line 2—2 of Fig. 1 with the section confined to the device itself and which is to say separate and apart from the pipe.

Fig. 3 is a fragmentary side elevational view looking in the direction of the arrows 3—3 of Fig. 2; and

Fig. 4 is a reduced-scale side elevational view of the pipe-and-guard assembly to indicate the manner in which the guard is precluded from being pushed downwardly into the tank.

The device of the present invention is produced from one continuous piece of spring wire bent from one end to the form of a receding or incurved helix, denoted by the numeral 5, and with the initiating convolution, as 6, having a diameter somewhat larger than the inside of the filler pipe to which the device is to be applied. From the terminating convolution the wire is caused to extend diametrically, as at 1 (Fig. 2), at substantial right-angles to the axis of the helix, and thence is bent downwardly for an appreciable distance whereat the wire is doubled back upon itself to produce parallel branches 8 and 9 leading to and from a terminal loop 10. The return branch 9 is caused to again enter the helix 5 and is carried upwardly as a prolongation 11 with the upper end terminating in the plane of origination of the helix.

2

Referring to Figs. 1 and 4 for an understanding of the installation and functioning of the device, the numerals 12 and 13 represent the in-line sections of the usual filler pipe for a gasoline tank (not shown), and which customarily are coupled by a flexible hose connection 14. At the head end of the outermost pipe section typical construction provides an integral capping sleeve 15 bent over at the top to present an in-turned flange 16. The filler cap (not shown) for this type of filler pipe usually has horns upon its underside which hook under the flange for holding the cap in place.

Assuming now that it is desired to install my device to a filler pipe it is only necessary that the small end of the unit be fitted into the open top of the pipe, and a screwdriver is then applied to bear by its end against the diametrical cross-arm 7 and the unit can be easily threaded into the pipe. As the convolution 6 finally snaps into position below the flange 16 the device is thereupon caused to be locked against withdrawal. It is quite evident that any attempt to introduce a siphon tube is blocked by the progressively smaller convolutions of the helix and the cross-arm 7 which lies at the base of the latter. Should an individual attempt to push the device downwardly, the loop 10, being held by the spring characteristic of the wire in bearing engagement against the wall of the pipe, will ultimately hang up as it moves below the pipe 12 and then engages with the end shoulder 17 of the lower pipe section 13.

While there is herein shown and described the embodiment of the invention now preferred by me, it is obvious that numerous modifications might be resorted to without departing from the spirit of the invention, and it is my intention that no limitations be read into the hereto annexed claims other than such as are expressly introduced to differentiate the present advance from prior knowledge in the art.

What I claim is:

1. A device for theft-proofing a gasoline tank's filler pipe of the described character, and namely a filler pipe composed of joined in-line upper and lower pipe sections of which the upper section has a curve within its length and the lower section presents an upwardly exposed shoulder at its point of juncture with the upper section, said device comprising one continuous piece of spring wire bent to the form of an incurved helix with the initiating convolution having a normal diameter somewhat larger than the inside diameter

of the upper pipe section, and with the opposite end of the wire being carried for an appreciable distance beyond the apical end of said inturned helix as a substantial axial prolongation of the said helix, the projecting end of said axial prolongation protecting the device against being pushed downwardly through the pipe and into the tank by coming into contact with and hanging up against said upwardly exposed shoulder of the lower pipe section.

2. The theft-proofing device of claim 1 in which the wire section which forms said axial prolongation is bent back upon itself with the free end thereof re-entering the helix and within the lat-

ter running generally longitudinal to the axis for very nearly the full length of the helix.

ARTHUR R. GLIDDEN.
